COOLING TOWER

Leon T. Mart, Johnson County, Kans.

Application September 18, 1935, Serial No. 41,049

5 Claims. (Cl. 261—109)

This invention relates to forced draft cooling towers of that class particularly designed for installation on roofs of buildings and in locations of restricted or limited circulation of cool fresh air, as in the neighborhood of surrounding office buildings, smoke stacks, steam vents, and the like. One of my objects is to produce a cooling tower so constructed that the efficiency of towers installed in such undesirable locations may be increased by taking the air from a point above the tower, rather than from adjacent the lower end thereof as is now standard practice.

Another object of the invention is to produce a construction in which the fan and motor are spaced a relatively great distance above the roof, if on a building, thereby effectively reducing the volume of noise or sound transmitted to the building.

A further object of the invention is to increase the efficiency of towers by taking air from a relatively high location rather than from adjacent the lower end of the tower, since it is well known that under ordinary conditions, the air at an elevated location is cooler than that lying next the ground or roof.

A still further object of the invention is to produce a tower in which the air is delivered to the tower in a vertical direction and then is spread horizontally in all directions so that the fan may be mounted to discharge vertically downward and be protected against a stiff breeze or gusty air, regardless of the direction from which the wind may blow.

With the general objects named in view and with the further object of producing a cooling tower of the character described which readily lends itself to architectural treatment for blending into an edifice, or which may be handled as a primary architectural feature (since the fan, pipes, valves, etc., may all be readily concealed), the tower of the invention consists in certain novel and useful features of construction and organization of parts as hereinafter described and claimed; and in order that it may be fully understood, reference is to be had to the accompanying drawing, in which:

Figure 1 is a central vertical section through a tower embodying the invention.

Figure 2 is a top plan view of the tower as shown in Figure 1.

Figure 3 is a top plan view of a modification showing a circular cooling tower embodying the invention.

Figure 4 is a vertical section through the tower of Figure 3, with the upper part cut away.

In the cooling tower as it is shown in Figures 1 and 2, 1 and 2 are upright casings, both being illustrated as of wood construction, although, of course, they may be made of any desirable material. In the drawing, the tower 2 is shown as 5 of double wall construction to prevent water leakage, while the tower 1 is of single wall construction for purposes of economy, since it is the air conduit, casing or pressure chamber as will hereinafter appear. The casing 1 is arranged centrally of the casing 2 and is of smaller cross-sectional area and is of greater height, the lower end of said casing 1 being spaced some distance above the water collecting basin 3 as by being supported on a plurality of piers 4 resting on the bottom of 10 the collecting basin, the spaces between the piers constituting air discharge passages 5. As the air is discharged downwardly through the casing 1, as will hereinafter appear, it has a plenum 15 chamber effect as it forcibly escapes through the 20 passages 5 in all directions upon striking the surface of the water or the bottom of the collecting basin.

Mounted within the casing 1 is a fan 6 which 25 draws air downwardly through the casing and discharges it into the lower end of the casing 2. The casing 2 may be closed at its upper end by a drift eliminator 7, and below said eliminator any suitable type of water distributing apparatus 30 may be installed, such as water discharge troughs and drip boards, upwardly or downwardly discharging spray nozzles, or other apparatus for finely dividing the water for intimate counter flow relation with the air being circulated up through the casing 2. For convenience, in the drawing, a 35 series of downwardly discharging water spray nozzles 8 are shown. In the type of construction here shown it will be apparent that other things remaining constant, the velocity with which the air exits through the opening 5 will depend to 40 some extent upon the pressure due to the rise and fall of the water level changing the width of the openings 5 through which the air is discharged.

In the tower as shown in Figures 3 and 4, the 45 air casing 9 and the cooling or water casing 10 are illustrated as of cylindrical shape. Also, the collecting basin is shown as of annular shape, and its inner wall supports four piers 12 which carry the air casing 9, whose lower end is closed 50 by a baffle or deflector 13 for radially distributing the air through the spaces 14 between the piers 12. This baffle construction is, of course, adaptable for use with the type of construction shown in Figures 1 and 2, and its use avoids change 55

in the velocity of the air as delivered due to a variation in the depth of water standing in the collecting basin. In Figures 3 and 4 the fan and spray nozzles are omitted.

5 It is also to be noted that the cooling or water casings may be arranged, if necessary, at one, two or three sides of the air casing, according to the conditions to be met at the point of installation, but obviously none of these arrangements are as desirable as the concentric arrangement herein described. Also the casings may be of masonry, wood, metal or any other structural material.

From the above description, it will be apparent 15 that while I have described and illustrated the preferred embodiment of the invention, it is to be understood that I reserve the right to all changes within the spirit of the invention and without the ambit of the prior art.

20 I claim:—

1. A cooling tower comprising a pair of upright casings of unequal height, said casings being open at their upper ends and having a connecting passage at their lower ends, water distributing apparatus adjacent the upper end of the shorter casing to deliver water in comminuted form for gravitating downwardly through said casing, and means for drawing in air at the top of the taller casing and discharging it downwardly 25 through the casing and connecting passages into the shorter casing, such air flowing upwardly in counter-flow contact with the water in said shorter casing and being discharged through the open upper end of the shorter casing in parallelism to the taller casing.

2. A cooling tower comprising a pair of coaxially arranged casings communicating at their lower ends, the outer casing being of less height than the inner casing, water distributing apparatus arranged in the outer casing to evenly distribute water in finely divided form over its cross-sectional area for gravitating downwardly, and means in the inner casing for drawing air down through the same and discharging it into the lower end of the outer casing for counter-flow contact with the downwardly moving water; said outer casing being open at its upper end for discharging the air in parallelism to the inner casing.

30 3. A cooling tower comprising a pair of up-

right casings of unequal height, said casings communicating with the atmosphere at their upper ends and having a connecting passage at their lower ends, water distributing apparatus adjacent the upper end of the lower casing, 5 means for discharging air downwardly through the taller casing, and a relatively horizontal baffling surface at the lower end of the taller casing for radially distributing the air through the connecting passage into the shorter casing 10 for counter-flow contact with the falling water, the upper end of the shorter casing being open for discharging the air in parallelism to the taller casing.

4. In apparatus of the character described, a 15 collecting basin, a cooling tower built above the collecting basin and having relatively air and liquid tight walls and adapted for air discharge through its upper end, a relatively air and liquid tight supply duct within the cooling tower 20 having its lower end terminating above the maximum water level in the collecting basin and its upper end projecting vertically above the cooling tower, water distributing apparatus adjacent the upper end of the cooling tower, and means 25 impelling air down through the duct for distribution at the lower end of the tower for upwardly flowing in counter-flow contact with the water and discharge from the upper end of the tower in parallelism to the supply duct. 30

5. In apparatus of the character described, a collecting basin having outer and inner walls to form a central dead area, a cooling tower having outer and inner walls corresponding to the outer and inner walls of the collecting basin, the 35 inner walls of said cooling tower terminating some distance above the inner walls of the collecting basin and at their upper ends projecting above the outer walls which are open at their upper ends, water distributing apparatus within 40 the outer walls adjacent their upper ends, and means enclosed by the inner walls for causing air to pass downwardly between the same and be distributed in the space between the outer and inner walls for counter-flow relation with 45 the water passing downwardly therein and for discharging the air through the open upper end of the outer walls in parallelism to the taller walls.
